UNITED STATES PATENT OFFICE.

JOHN J. BURNS AND WILLIAM H. FLYNN, OF SHORTSVILLE, NEW YORK.

CULINARY UTENSIL.

1,241,818.

Specification of Letters Patent.

Patented Oct. 2, 1917.

Application filed January 26, 1916. Serial No. 74,380.

To all whom it may concern:

Be it known that we, JOHN J. BURNS and WILLIAM H. FLYNN, citizens of the United States, residing at Shortsville, in the county 5 of Ontario and State of New York, have invented certain new and useful Improvements in Culinary Utensils, of which the following is a specification.

This invention relates to improvements in 10 culinary utensils or vessels, and has for one of its objects to provide a simply constructed device of this character of increased efficiency and wherein means are provided for disposing of the fumes rising from the utensil, and wherein the labor incident to assembling the parts is materially decreased.

With these and other objects in view, the invention consists in certain novel features of construction as hereinafter shown and described, and then specifically pointed out in the claims; and in the drawings illustrative of the preferred embodiment of the invention.

Figure 1 is a perspective view from beneath of the cover portion of the improved device;

Fig. 2 is a perspective view from above of the receiver portion of the utensil;

Fig. 3 is an enlarged sectional detail illustrating the construction of the holding device between the receiver and the cover;

Fig. 4 is a sectional detail illustrating the construction of the device for disposing of the fumes.

Corresponding and like parts are referred to in the following description and indicated in all the views of the drawings by the same reference characters.

The improved device comprises a receiver 40 for the material to be cooked and a cover for the same. These parts may be of any required size and of any required shape, but are preferably circular. The receiver is represented conventionally at 10 and provided 45 with a relatively wide flange 11 at its upper edge, while the cover, represented conventionally at 12, is provided with a corresponding lateral flange 13 at its lower edge, the two flanges engaging face to face, as 50 illustrated in Figs. 3 and 4, when the cover is disposed upon the receiver.

At one portion, one of the flanges is formed with a projection, while the other flange is formed with a socket to receive the 55 projection when the receiver and its cover are assembled. The projection is preferably

upon the flange of the receiver, while the socket is preferably in the flange of the cover, as illustrated in Fig. 3. The projection is preferably struck up by a suitable die at its outer edge, while the socket is likewise struck up from the flange of the receiver by a suitable die. The projection is represented conventionally at 14, while the socket is represented conventionally at 15. 60 Preferably the projection will be relatively short, as illustrated in Fig. 4, while the socket will be relatively long so that a considerable degree of play is permitted rotatively between the cover and the receiver. 65 In locating the cover upon the receiver the socket can thus be more readily disposed over the projection, and will not require the nicety of adjustment which would otherwise be necessary.

Formed within the receiver 10 is a tubular member, represented as a whole at 16. The member 16 communicates through the bottom of the receiver, as represented at 17, and is of less length than the height of the 80 receiver so that a space is left between the top of the conduit 16 and the top of the receiver, as illustrated in Figs. 2 and 3. The tubular member 16 may be located at any desired point upon the vertical wall of the 85 receiver, but will preferably be spaced a short distance from the projection 14, as illustrated in Fig. 2. By this simple means when the parts are united and the utensil disposed over the griddle opening of a stove 90 the fumes which arise from the material being cooked will pass downwardly within the tube 16 and into the fire and thence be conducted, together with the smoke and other products of the combustion, into the 95 chimney and prevented from passing into the room in which the utensil is located. It will be noted that the receptacle and its cover are freely separable so that access may be readily had to the contents thereof and 100 also to facilitate cleaning the parts when necessary. It will also be noted that the upper surface of the projection 14 and the wall of the socket 15 are curved or rounded so as to form in effect a hinge when the parts are 105 assembled and thus permit the cover to be slightly tilted when desired without liability of accidental displacement of the parts.

The improved device is simple in construction, can be inexpensively manufactured and is convenient for use and enables the operator to readily locate the cover 110

upon the receiver, and at the same time elevate the cover at one side without totally removing it from the receiver by the coaction of the projection 14 and the depression 15, 5 as illustrated by the dotted lines in Fig. 3.

Having thus described the invention, what is claimed as new is:—

1. A cooking vessel including freely separable members provided with flat coacting 10 laterally extending flanges, the peripheral edges of which are smooth and unobstructed, the flat face of the flange of one of the members being provided with a socket and the flat face of the flange of the other member 15 with a projection adapted to enter the socket, the socket being of greater length than the projection thereby to permit rotative movement of one member with respect to the other.

- 20 2. A cooking vessel including freely sep-

arable members each provided with a laterally extending circumferential flange the peripheral edge of which is smooth and unobstructed, said flanges being provided with coacting faces flat throughout their entire 25 widths, the flat face of the flange of one member being upstruck to form a socket and the flat face of the flange of the other member being upstruck to form a projection of less length than the socket and adapted to enter the latter, the wall of the socket being curved for engagement with a correspondingly curved face on the projection whereby to permit one of the members to be tilted 30 with respect to the other without entirely separating said members.

In testimony whereof we affix our signatures.

JOHN J. BURNS. [L. S.]
WILLIAM H. FLYNN. [L. S.]
